UNITED STATES PATENT OFFICE

96,485

DESIGN FOR A RADIATOR

Raymond Loewy, New York, N. Y., assignor to Sears, Roebuck and Co., Chicago, Ill., a corporation of New York

Application January 4, 1935, Serial No. 54,724

Term of patent 7 years

To all whom it may concern:

Be it known that I, Raymond Loewy, a citizen of France, residing at New York city, in the county of New York and State of New York, have invented a new, original, and ornamental Design for a Radiator, of which the following is a specification, reference being had to the accompanying drawing, forming part thereof.

The figure is a perspective view of a radiator showing my new design.

I claim:

The ornamental design for a radiator substantially as shown.

RAYMOND LOEWY.
